UNITED STATES PATENT OFFICE

2,627,227

RUBBER STAMP PENCIL COMBINATION

Albert D. Claggett, Denver, and David M. Miller,
Hugo, Colo.; said Claggett assignor to said
Miller

Application January 7, 1949, Serial No. 69,794

1 Claim. (Cl. 101—333)

1

This invention relates to a pocket rubber stamp, and has for its principal object the provision of a simple, neat, compact, easily used implement which will provide both a writing pencil or pen and a rubber stamp, and which can be conveniently carried in the pocket, similarly to the usual pocket pen and pencil.

Another object of the invention is to provide means for simultaneously concealing and inking the rubber stamp portion of the device when not in use.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved pencil and rubber stamp device;

Fig. 2 is a similar view partially broken away to show the interior construction;

Fig. 3 illustrates the device with the rubber stamp exposed ready for use;

Fig. 4 is a side view of the improved instrument, looking in the direction of the arrow, Fig. 3;

Fig. 5 is a bottom view of the rubber stamp ready for use;

Fig. 6 is a detail sectional view of the rubber stamp portion of the device; and

Fig. 7 is a cross-section through the cap employed on the improved instrument.

The improved rubber stamp is designed to be mounted upon any of the usual mechanical pens or pencils. In the drawing, a mechanical pencil of any of the conventional types is indicated at 10, with its pencil lead at 11. The rear extremity of such a pencil is usually open for receiving an eraser or an ornamental plug.

This device is applied in this open extremity and consists of a tubular sleeve 12 from which a semi-cylindrical arm 13 extends. The arm is preferably a portion of the sleeve 12 formed by cutting back one side of the latter.

The extremity of the arm 12 terminates in two hinge ears 14 through which a hinge pin 15 extends. A U-shaped hinge bracket 16 is rotatably mounted on the pin 15. The bracket 16 is soldered or otherwise secured to the back of a channel-shaped type bar 17.

The position of the hinge pin 15 relative to the bar 17 is such that the latter may fold into the concave side of the arm 13, as shown in Fig. 2, or may fold transversally of the arm 13, resting against the extremity of the latter, as shown in Fig. 3. The bar 17 is constantly urged to the position of Fig. 3 by means of a spring 18 which is

coiled about the pin 15, with its extremities bearing against the arm 13 and the bar 17.

The channel shape of the bar 17 is designed to frictionally engage a plurality of rubber type 19 forming the word or words which it is desired to impress with the stamp. The bar 17 is held in the folded position of Fig. 2 by means of a cylindrical cap 20 which fits over the extremity of the pencil 10. The cap is lined with a cylindrical, saturated ink pad 21 of felt or similar absorbent material.

When being used as a pencil, the cap 20 remains in place. When it is desired to use the rubber stamp, the cap is simply removed, allowing the spring 18 to snap the bar 17 to the cross-wise position of Fig. 3, presenting its inked type faces for use. To return the stamp it is only necessary to slip the cap 20 over the right-hand extremity of the bar 17 in Fig. 3, and then to turn the cap into alignment with the pencil 10, allowing it to be pushed into place thereover, with the type faces resting against the saturated ink pad.

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A rubber stamp adapted to be mounted upon a pencil, comprising: a tubular sleeve arranged to receive the rear extremity of the pencil; an arm extending from said sleeve alongside of and parallel to the axis thereof; a type-holding bar; hinge means mounting said bar on the extremity of said arm so that the bar may be folded from a position parallel to said arm to a position across the extremity of the latter; a tubular cap member surrounding said arm and said bar when the latter is in the above parallel position, one extremity of said cap being open to receive the extremity of said pencil; and a tubular, absorbent lining within said cap forming an ink pad completely surrounding said bar, the absorbent surface of said lining facing inwardly and lying in contact with said bar for inking the type therein.

ALBERT D. CLAGGETT.
DAVID M. MILLER.
